DISPLAY RACK FOR DECORATORS' SAMPLE
BOOKLETS OR THE LIKE

Lois Dauntsey Smith, Jackson, Miss.

Application September 8, 1954, Serial No. 32,194

Term of patent 14 years

(Cl. D80—9)

Fig. 1.

Fig. 2.

Fig. 3.

Fig. 4.

Fig. 1 is a front perspective view of a display rack for decorators' sample booklets or the like, showing my new design, with the panels in open position;

I claim:

The ornamental design for a display rack for decorators' sample booklets or the like, as shown.
